(57) **CLAIM**

The ornamental design for a mobile device with multiple camera lenses, as shown and described.

DESCRIPTION

FIG. 1 is a front elevation view of a mobile device with multiple camera lenses;

FIG. 2 is a rear elevation view thereof;

FIG. 3 is a right side elevation view thereof;

FIG. 4 is a left side elevation view thereof;

FIG. 5 is a top plan view thereof; and

FIG. 6 is a bottom plan view thereof.

The broken lines in FIGS. 1-6 illustrate portions of the mobile device with multiple camera lenses that form no part of the claimed design.
